Inventor:
William W. Kirchner

United States Patent Office.

WILLIAM M. KIRCHNER, OF PITTSBURG, PENNSYLVANIA.

Design No. 4,755, dated April 4, 1871.

DESIGN FOR A JELLY-GLASS.

The Schedule referred to in these Letters Patent and making part of the same.

To all whom it may concern:

Be it known that I, WILLIAM M. KIRCHNER, of Pittsburg, in the county of Allegheny and State of Pennsylvania, have invented a new and improved Design for Jelly-Glass; and I do hereby declare the following to be a full, clear, and exact description thereof, reference being had to the accompanying drawings forming part of this specification, in which—

Figure 1 is a perspective view of a jelly-glass made after my improved design; and

Figure 2 is a like view of the same with the cap.

My design consists in a jelly-glass having a hexagonally-shaped mouth, and a hexagonally-shaped cap, with flanged edges to fit over the mouth.

Around the mouth of the glass *a* is a bead, *b*, either continuous and unbroken or broken at intervals.

The cap *c* is of like shape, so as to fit onto the mouth of the glass *a*.

The edges of four of the sides of the cap *c* are folded down and under, so as to fit around the bead, as at *c'*,

and the edges of the other two sides are bent down slightly, so that they may be slipped or sprung over the bead, as at *c''*.

This cap slides onto the mouth of the glass, the folded sides *c* fitting against the bead *b* on four sides, and the sides *c''* slipping over the bead on the other two sides.

What I claim as my improved design, and desire to secure by Letters Patent, is—

1. A design for a jelly-glass having a hexagonally-shaped mouth, as described and shown.

2. A design for a hexagonally-shaped cap for a hexagonally-shaped jelly-glass, as described and shown.

In testimony whereof I, the said WILLIAM M. KIRCHNER, have hereunto set my hand.

WILLIAM M. KIRCHNER.
